UNITED STATES PATENT OFFICE.

WILLIAM H. WARD, OF BOSTON, MASSACHUSETTS; HENRY H. COTTON
EXECUTOR OF SAID WARD, DECEASED.

WATER-SUPPLYING APPARATUS FOR WATER-CLOSETS.

SPECIFICATION forming part of Letters Patent No. 449,768, dated April 7, 1891.

Application filed December 29, 1888. Serial No. 294,930. (No model.)

To all whom it may concern:

Be it known that I, WILLIAM H. WARD, of Boston, in the county of Suffolk and State of Massachusetts, have invented certain new 5 and useful Improvements in Water-Supply Apparatus for Water-Closets, of which the following is a specification.

This invention has for its object to provide simple and effective means for operating the 10 outlet-valve of a water-closet supply-tank, so as to give a limited preliminary wash when the closet-seat is depressed and a longer second wash when the seat is released.

The invention consists in the improvements which I will now proceed to describe 15 and claim.

In the accompanying drawings, forming a part of this specification, Figure 1 represents a side view of a water-closet supply-tank having 20 my improvements. Fig. 2 represents a section on line $x-x$, Fig. 1, looking toward the left. Fig. 3 represents a modification.

The same letters of reference indicate the same parts in all the figures.

25 In the drawings, a represents a supply-tank having a supply-cock b and an outlet-valve c , said cock and valve being of any suitable construction. The supply-cock is provided with a lever d , pivoted at one end to the casing of the 30 cock, and having at its free end a float d' , which is supported by the water in the tank. The inner end of the lever is provided with an arm which bears on a valve within the cock-casing, and closes the valve when the water 35 in the tank raises the float to a predetermined height. When the water falls, the valve opens and admits more water, as usual. The stem e of the valve has a rod e' , which 40 may be a continuation of the stem, but is here shown as connected thereto by a link f . Said rod passes through a vertical sleeve or guide g , affixed to the top of the tank, and has an enlargement or collar h above said sleeve.

i represents a weighted operating-lever pivoted at j' to an ear or bracket affixed to the 45 top of the tank, and having a weight i' attached to its longer arm and a pivoted toe piece or latch j on its shorter arm, said toe-piece being adapted to yield upwardly, but

being rigidly seated on the lever against 50 downward pressure. The operating-lever has an arm i'' , which is connected by a rod m with one arm of a bell-crank lever n , which is pivoted at n' to an ear on the tank, and has its other arm connected by a rod, chain, or other suitable means with the vertically-movable 55 seat of a water-closet.

The described connection between the closet-seat and the operating-lever has in itself no novelty, and as the operation of a 60 vertically-movable seat on a valve-operating weighted lever in substantially the manner here indicated is well understood, I do not deem it necessary to show the seat and the means whereby it is connected to the lever n . 65

o represents a short lever pivoted at p to a fixed standard q , and having one end in position to act, as hereinafter explained, on the valve-rod collar h , and the other end in position to be acted on by an arm or projection 70 r , formed on or affixed to the operating-lever.

s represents a bent lever pivoted at t to a standard u , affixed to the tank a , and having a projection or detent s' , which passes through and is guided by a slot in the standard u and 75 a weight s'' , which normally holds said detent in position to engage the valve-rod collar h when the latter is raised by the operating-lever, as hereinafter described. On the detent-lever s is formed an arm v , the outer 80 end of which supports a rod w , which extends downwardly into the tank, and is provided with a loop or slot w' at its lower end, through which the float-lever d extends. Said rod is vertically adjustable by means of a nut w'' , 85 screwed on its threaded upper end and bearing on the arm v .

Operation: When the closet-seat is depressed by the weight of the occupant, the operating-lever i is turned by the movement 90 of the seat imparted through the described connection, the end of the lever having the stud r being thus depressed. The stud in its downward movement bears on the pivoted lever o and raises the end thereof, which bears 95 on the valve-rod collar h , thus causing said lever to raise the valve and give the preliminary wash, the pivoted toe piece or latch j of

the lever *i* being moved below the collar *h* by the same movement. The lever *o* is raised out of contact with the collar *h* after the latch *j* has moved below the latter, and the valve 5 then drops to its seat, the latch *j* remaining below the collar, as shown in dotted lines in Fig. 1. When the occupant of the closet-seat rises and releases the seat, the weighted end of the lever *i* (now raised) falls by gravitation, thus raising the latch-piece *j* on its opposite end and causing the latter by its above-described engagement with the collar *h* to raise the valve, and thus give the second wash, the collar *h* being raised at this time high 15 enough to be engaged by the detent *s'* on the weighted lever *s*, as shown in dotted lines in Fig. 2. Said detent keeps the valve raised and prolongs the second wash until the water in the tank falls sufficiently to bring the 20 float-lever *d* against the lower end of the slot *w'* in the connecting-rod *w*, after which the lever *s* is moved by the continued descent of the float-lever, and the detent is thereby withdrawn from under the valve *h*, whereupon 25 the valve drops to its seat and closes the outlet, after which the water admitted through the supply-cock, which was opened by the descent of the float-lever, raises said float-lever and allows the weighted detent-lever *s* to resume 30 its normal position, restoring the detent to position to engage the collar *h* when next the valve is lifted by the latch *j*. This mechanism is simple in construction and effective in its operation and is not liable to get out of 35 order.

A modification is shown in Fig. 3, in which I substitute for the preliminary wash-lever *o* a lever *2*, located below the top of the tank, and is pivoted at *3* to a fixed arm extending 40 downwardly into the tank. One end of the lever *2* is forked, its branches projecting under a collar *h'* on the valve-stem *e*. To the other end of the lever *2* is pivoted at *4* a weighted latch *5*, which is held by its weight against a 45 shoulder or stop on the lever *2*, so that it cannot tip independently under pressure exerted in the direction indicated by the arrow in Fig. 3, but yields or tips independently under pressure in the opposite direction. The operating-lever *i* is provided with a downwardly-projecting arm *6*, which, when the operating-lever is moved by the depression of the closet-seat, presses against the weighted latch *5* in the direction indicated by the arrow, and thereby 50 causes said latch to raise the forked end of the lever *2*, and thus raise the valve for the preliminary wash. The arm *6* passes beyond and releases the latch *5* and lever *2* after the toe-piece *j* of the operating-lever has passed 55 below the collar *h* on the operating-rod *e'*, so that the said toe-piece is in position to raise the valve, as above described, for the second wash. When the operating-lever *i* is resuming its normal position after the release of 60 the closet-seat, the arm *6* on said lever moves back over the latch *5*, the latter yielding un-

til the arm *6* passes beyond it, and then resuming its operative position. The operation of the apparatus as a whole when this modification is used is precisely the same as 70 above described, the lever *2* performing the same functions as the lever *o*, first described.

For the sake of convenience in the wording of the claims, the movement of the operating-lever by the depression of the closet-seat is termed the "preliminary movement," 75 while the movement of said lever which follows the release of the seat is termed the "final movement." 80

I claim—

1. In a water-closet supply-tank, the combination, with the outlet-valve and the supply-cock float-lever, of the weighted operating-lever having an arm or projection, a connection through which said lever is given a preliminary movement and a final movement, as described, a collar connected with the valve, a pivoted latch on said lever, which is placed in operative relation with the valve-collar by the preliminary movement of the operating-lever, and thereby adapted to raise the valve during the final movement of said lever, a valve-lifting lever fulcrumed on a fixed standard and acted on by said 85 arm or projection of the operating-lever, whereby the valve is first raised and then released during the preliminary movement of the operating-lever, a detent-lever fulcrumed at one end adjacent to said former 90 levers and having a weight at its other end, and designed to engage the valve-collar when the latter is raised by the final movement of the operating-lever and connected 95 between said detent-lever and the float-lever, whereby the detent is displaced and caused 100 to release the valve by the depression of the float, as set forth. 105

2. In a water-supply tank, the combination, with the outlet-valve and the supply-cock, of the weighted operating-lever having an arm or projection, a connection through which said lever is given a preliminary movement and a final movement, as described, a collar connected with the valve, a pivoted 110 latch on said lever, which is placed in operative relation with the valve-collar by the preliminary movement of the operating-lever, and thereby adapted to raise the valve during the final movement of said lever, a valve-lifting lever fulcrumed on a fixed standard and acted on by said arm or projection of the operating-lever, whereby the valve is first 115 raised and then released during the preliminary movement of the operating-lever, a lever fulcrumed at one end adjacent to said former levers and having a weight at its other end and a detent designed to engage 120 the valve-collar when the latter is raised by the final movement of the operating-lever, 125 the arm *v*, projecting from said latter lever and having an outer forked end, a rod *w*, 130

having a loop or slot at its lower end and an
adjustable nut at its upper end engaged by
said forked end, and the float-lever having
its end extended through said loop or slot,
5 substantially as set forth.

In testimony whereof I have signed my
name to this specification, in the presence of

two subscribing witnesses, this 15th day of
December, A. D. 1888.

WILLIAM H. WARD.
